BUCKET CLEANER FOR TRENCH DIGGING MACHINES

William H. Hellums, Dawson, Tex.

Application November 26, 1947, Serial No. 788,281

4 Claims. (Cl. 37—90)

1

My invention relates to improvements in trench digging machines for use especially, although not necessarily, in digging graves.

The primary object of my invention is to provide an efficient, light weight machine designed to be easily and quickly moved from place to place, for instance, in a cemetery, and for digging graves with clean-cut side and end walls without causing cave-ins and the like.

Another object is to provide a machine for the purpose above set forth adapted for operation while digging a grave to elevate the earth dug out of the grave above the mouth of the grave for convenient disposal at one side of the grave.

Still another object to provide a machine for the above purposes which is power operative to travel over the grave location and dig and elevate the earth dug, as above set forth.

Still another object is to provide a power operated grave digging machine which is simple in construction, involves a minimum number of parts, and is comparatively inexpensive to manufacture, operate and service.

Other and subordinate objects also within the purview of my invention, together with the precise nature of my improvements, will be readily understood when the succeeding description and claims are read with reference to the drawings accompanying and forming part of this specification.

In said drawings:

Figure 1 is a view in side elevation of my improved machine in a preferred embodiment thereof;

Figure 2 is a view in front elevation partly broken away;

Figure 3 is a view in horizontal section, partly in plan, taken on the line 3—3 of Figure 1 and drawn to a larger scale;

Figure 4 is a fragmentary view in vertical longitudinal section, taken on the line 4—4 of Figure 3;

Figure 5 is a fragmentary view in perspective of two of the troughs of the earth digging and elevating conveyor viewed from the rear sides thereof;

Figure 6 is a similar view of said troughs viewed from the front sides thereof;

Figure 7 is a fragmentary view in plan of the earth digging and elevating unit;

Figure 8 is a fragmentary view in side elevation of the upper end of the same;

Figure 9 is a fragmentary view partly in section and partly in elevation of the upper end of the earth digging and elevating unit drawn to a larger scale; and

2

Figure 10 is a fragmentary view in horizontal section taken on the line 10—10 of Figure 1 and drawn to a larger scale.

Referring now to the drawings by numerals, in the illustrated embodiment thereof, the machine of my invention comprises a wheel-supported carriage C having a frame 1 formed with a pair of parallel side bars 2 of any suitable length connected together by front and rear end cross bars 3, 4, all preferably of channel iron form.

At the front end thereof, the carriage frame 1 is supported by a pair of grooved front wheels 5 rotatable on the ends of a channel axle bar 6 pivoted by a king pin 7 to an overlying sector plate 8 extending rearwardly from said front cross bar 3 and bolted thereto, as at 9.

At the rear end thereof, said frame 1 is supported by a pair of rear wheels 10, like the wheels 5, rotatably mounted on the ends of a channel cross bar 11 underlying said frame 1 and suitably fixed thereto.

The pairs of front and rear wheels 5, 10 are spaced apart in the pairs and grooved to run on parallel rails 12, for instance, square timbers laid upon opposite sides of a grave location.

Acruately slotted, rearwardly extending bars 13 on the front cross bar 3 receive in the slots 14 thereof bolts 15 on the axle bar 6, said bars 13 and bolts 15 providing for pivotally adjusting the axle bar 6 into set position to align the front wheels 5 with the rear wheels 10, as occasion may require.

At the rear of the carriage frame 1 is a platform 16 supported by the rear cross bar 4 and a pair of laterally spaced channel cross bars 17 connecting the side bars 2 intermediate the cross bar 11 and the transverse center of said frame 1. The platform 16 serves for general utility and other purposes presently seen.

A motor 18 of conventional form is set into the platform 16 and suitably secured on the cross bars 17 with a reverse gear housing 19 out of which a drive shaft 20 extends toward one side of the carriage frame 1 and is operatively connected by reduction gears 21, 22 to a propeller shaft 23 extending parallel with said shaft 20 beyond the same side of said frame 1 across one rear wheel 10 and through a suitable bearing 24 on the platform 16.

A gear pinion 25 freely rotatable on the outer end of the propeller shaft 23 meshes with a larger gear wheel 26 fixed, as shown, on the face of said rear wheel 10, whereby the motor 18 may be operatively connected to said wheel 10 to drive the same.

A motor reverse lever 27 extends out of said

gear housing 19 for reversing the drive shaft 20 and a suitable lever operative clutch 28 provides for clutching the gear pinion 25 to the propeller shaft 23.

The gear 26 is adapted to mesh with a rack bar 29 provided on one rail 12. Thus, the carriage C is adapted to be moved by the described motor drive in opposite directions along the rails 12 and longitudinally of a grave, or grave location. The drive shaft 20 extends through a bearing 30 on the platform 16 and has fast on the outer end thereof a beveled gear 31, the purpose of which will presently appear. A fuel tank T for the motor 18 is suitably mounted on the platform 16.

Forwardly of the platform 16, a pair of skeleton angle iron frames 32 arise from the side bars 2 in opposite relation with upper horizontal bars 33 and are braced against each other by cross tie bars 34 suitably connected to the upper corners thereof.

Intermediate said frames 32 is an upright, vertically elongated, earth digging and elevating unit 35 of conveyor form comprising a pair of upright side frame bars 36 suitably connected together intermediate the ends thereof by vertically spaced cross tie members such as shown at 37.

A pair of upper and lower transverse rollers 38, 39 are suitably journaled at the ends thereof in the upper and lower ends of said frame bars 36 to extend between said bars.

An endless earth digging and elevating link type conveyor 40 is trained around the rollers 38, 39 and which comprises transverse, slat-like troughs 41, the ends 42 of which form the links of the conveyor by means of which said troughs 41 are pivoted together, as at 43.

The troughs 41 are provided with transversely arcuate, concave, front sides 44 having longitudinal sharp digging edges 45. The front side 44 of each trough 41 is formed transversely on its inner face in an arc concentric to the pivotal axis of the preceding trough 41, that is, as regards the direction of travel of the troughs, and is also formed with a bottom, longitudinal lip 46 adapted to swing in the succeeding trough 41 with a wiping action against the inner face of said succeeding trough to empty the same as the troughs 41 pass around the front side of the upper roller 38.

Lateral lugs 47 on the rear side of the troughs 41 adapted to engage in center, circumferential grooves, as at 48, in the upper and lower rollers 38, 39, center the conveyor 40 on said rollers.

The described conveyor 40 is adapted to be driven by the following means. The before-mentioned beveled gear 31 meshes with a smaller beveled gear 49 on a horizontal stub shaft 50 journaled in a bearing 51 on an upright 52 on the platform 16, and also being journaled in a bearing 53 on one frame 32. A gear 54 on the shaft 50 meshes with a gear 55 on a horizontal worm shaft 56 journaled in bearings 57 on said frame 32. A worm 58 on the worm shaft 56 meshes with a worm wheel 59 fast on a transverse shaft 60 suitably journaled in bearing arms 61 on the frames 32 and having a pair of sprocket wheels 62 fast thereon above the lower roller 39 and intermediate said frames 32.

A pair of vertically extending sprocket chains 63 are trained around the sprocket wheels 62 and around a pair of higher sprocket wheels 64 fast on a transverse shaft 65 suitably journaled, as at 66, on the upper bars 33 of the frames 32.

The sprocket chains 63 are equipped with studs 67 and one run of said chains extends parallel,

vertically, with the front run of the conveyor 40 so that said studs are adapted to engage rear hooked edges 68 on the troughs 41 and thereby drive said conveyor 40 with a lifting action against the front run of said conveyor.

A clutch 69 on the stub shaft 50, shiftable by a clutch shifter lever 70 on the upright 52, provides for connecting said stub shaft 50 to the gear 54 for driving the worm shaft 56 to operate the sprocket wheels 62 so that the sprocket chains 63 will drive the conveyor 40 as above set forth.

The described earth digging and elevating unit 35 is mounted for vertical movement to lower the lower end of the conveyor 40 into the earth and raise said end out of the earth. The mounting for this purpose comprises opposite pairs of upper rollers 71 mounted in bearing brackets 72 on the upper bars 33 of the frames 32, and similar pairs of lower rollers 73 similarly mounted on bearing brackets 74 on the side bars 2, the frame bars 36 being interposed between the rollers of the pairs for vertical movement with the lower roller 39 of the conveyor 40 being below the lower rollers 73, as best shown in Figure 4.

Means are provided for moving the earth digging and elevating unit 35 vertically comprising the mechanism now to be described. A horizontal shaft 75 aligned with the stub shaft 50 is journaled in the before mentioned bearing 53 and a bearing 76 on one side bar 2, and to which the worm shaft 56 may be operatively connected by a pair of gears 77, 78 on said stub shaft 75 and the worm shaft 56 respectively, the gear 77 being freely rotatable on said shaft 75. A gear wheel 79 fast on said shaft 75 meshes with a vertical rack bar 80 secured to one frame bar 36 to extend along the same. A suitable clutch 81 is operative by a clutch shifting lever 81' to clutch said shaft 75 to the gear 77.

At the upper end of the combined earth digging and elevating unit 35, in front thereof, preferably, is an unloading cross conveyor 82 on which the conveyor 40 is designed to deposit earth and which is adapted to convey earth thereon to one side of the carriage C and unload the same onto the ground.

The unloading cross conveyor 82 comprises a substantially horizontal, endless belt 83 slanting downwardly toward one side of the carriage C and running on a pair of end rollers 84 journaled in suitable bearing brackets 85 on the frame bars 36. Beveled gearing 86 between one end of the upper roller 38 and the journal shaft 87 of one roller 84 provides a drive from said upper roller 38 of the conveyor 40 to said unloading cross conveyor 82.

Rotary scraping means for the front sides 44 of the troughs 41 is provided at the top of the combined earth digging and elevating unit 35, the basic element of which is a reel 88 extending parallel to and above the upper roller 38 and journaled at its ends in bearing arms 89 inclining upwardly and forwardly from the upper end of the frame bars 36 so that said reel 88 is disposed over the rear edge of the unloading cross conveyor 82 for a purpose presently seen.

Radial trough-like blades 90 on the reel 88, with longitudinal scraping edges 91, are arranged to be revolved by said reel so as to scrape the front sides 44 of the troughs 41 toward the unloading cross conveyor 82, and as each trough 41 reaches a position between the vertical center of the conveyor 40 and the rear edge of said cross conveyor 82. A sprocket and chain drive 92 between one end of the upper roller 38 and the reel

88 operatively connects the conveyor 40 to said rotary scraping means.

As shown in Figure 3, the rollers 38, 39 may be provided with enlarged ends 93 for spacing the troughs 41 of the conveyor 40 from said roller, intermediate said ends 93, to accommodate the hooked edges 68 of said troughs 41.

Referring now to the operation of the described machine in digging a grave. With the carriage C of the machine positioned on the rails 12 and said rails positioned along opposite sides of a grave location, the clutch 69 disengaged and the combined earth digging and elevating unit 35 being in its upward limit of movement with the lower end of the conveyor 40 clearing the ground, the carriage C may be run forwardly or rearwardly by the described motor drive for said carriage and under control of the clutch 23 and the reverse lever 27 so that digging may be started where desired. In this connection, with the clutch 69 disengaged, also the clutch 81, the combined earth digging and elevating unit 35 is held against lowering, under the influence of gravity, by the fact that the worm wheel 59 cannot operate the worm 58 and, therefore, said unit 35 is held suspended by the sprocket chains 63.

With the carriage C located over the grave location, as described, and the clutch 28 disengaged to disconnect the motor drive from the carriage C, the conveyor 40 may be set in motion by engaging the clutch 69, whereupon, with the drive shaft 20 rotating in the proper direction, the worm shaft 56 will be operated to operate the sprocket chains 63 and drive the conveyor 40, counter-clockwise as seen in Figures 1 and 4. In this direction of operation of said conveyor 40, the digging edges 45 of the troughs 41 are adapted to dig and the troughs 41 to be filled with earth and to elevate the earth dug. As each trough 41 travels to a point at the front sides of the roller 38 slightly above the unloading cross conveyor 83, the bottom lip 46 of a preceding trough 41 functions in the manner already described to expel the earth therefrom onto said conveyor 82 which conveys the earth to one side of the machine and unloads the same. As each trough 41 is thus emptied, the front side 44 thereof is scraped by the scraper blades 90 of the reel 88 in the manner already described, and, thus, the front sides 44 of the troughs 41 are cleaned of earth sticking thereto before repeat digging operations by said troughs. By engaging the clutch 81, with the conveyor 40 operating as described, the combined earth digging and elevating unit 35 may be lowered into the earth as required. By reversing the drive shaft 20, with the clutches 69, 81 engaged, said unit 35 may be raised, as desired. Obviously, the carriage C may be driven to feed the same along the grave location while the digging and elevating is being effected, and in a manner which will be clear from the preceding description.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

Having described the invention, what is claimed as new is:

1. In a machine of the class described, a wheel supported carriage, a motor drive for the car-

riage for causing the same to travel over a digging location, a combined earth digging and elevating unit including an upright endless digging and elevating conveyor, means to mount said unit on said carriage for vertical movement to lower said conveyor into the earth, means to move said unit vertically operative by said carriage drive, means to drive said conveyor by said last-named means, said conveyor comprising troughs constructed and arranged to each expel earth into a contiguous trough at one side of the conveyor, and means on said unit for scraping said troughs on the outside thereof after the earth has been expelled therefrom operative by said digging and elevating conveyor.

2. In a machine of the class described, a wheel supported carriage, a motor drive for the carriage for causing the same to travel over a digging location, a combined earth digging and elevating unit including an upright endless digging and elevating conveyor, means to mount said unit on said carriage for vertical movement to lower said conveyor into the earth, means to move said unit vertically operative by said carriage drive, means to drive said conveyor by said last-named means, said conveyor comprising troughs constructed and arranged to each expel earth into a contiguous trough at one side of the conveyor, and means on said unit for scraping said troughs on the outside thereof after the earth has been expelled therefrom operative by said digging and elevating conveyor comprising a reel with scraping blades thereon.

3. In a machine of the class described, a carriage for positioning over a digging location, a combined earth digging and elevating unit including an endless upright digging and elevating conveyor mounted on said carriage, means to drive said conveyor, said conveyor comprising troughs constructed and arranged to each expel earth into a contiguous trough at one side of the conveyor, and means on said unit for scraping said troughs on the outside thereof after the earth has been expelled therefrom operative by said conveyor.

4. In a machine of the class described, a carriage for positioning over a digging location, a combined earth digging and elevating conveyor mounted on said carriage, means to drive said conveyor, said conveyor comprising troughs constructed and arranged to each expel earth into a contiguous trough at one side of the conveyor, and rotary means on said unit for scraping said troughs on the outside thereof after the earth has been expelled therefrom operative by said conveyor.

WILLIAM H. HELLUMS.
